US00D661211S

(12) **United States Design Patent**
Hou

(10) **Patent No.:** **US D661,211 S**
(45) **Date of Patent:** **** Jun. 5, 2012**

(54) **DEVICE FOR HUMAN FACE RECOGNITION**

(75) Inventor: **Hsiang-Fei Hou**, Tu-Cheng (TW)

(73) Assignee: **Cheng Uei Precision Industry Co., Ltd.**, Tu-Cheng, Taipei Hsien (TW)

(**) Term: **14 Years**

(21) Appl. No.: **29/362,792**

(22) Filed: **May 31, 2010**

(51) **LOC (9) Cl. 10-05**

(52) **U.S. Cl. D10/104.1**

(58) **Field of Classification Search** D10/104.1, D10/106.1, 118; D14/383, 384; 340/5.82; 382/116, 124, 126

See application file for complete search history.

(57) **CLAIM**

The ornamental design for a device for human face recognition, as shown and described.

DESCRIPTION

FIG. 1 is a perspective view of a device for human face recognition showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets

FIG. 1

FIG. 2

FIG. 3

FIG. 4

FIG. 5

FIG. 6

FIG. 7
